METHOD OF AND APPARATUS FOR REMOVING PITS FROM METAL SHEETS

David E. Mulholland, Reading, Pa.

Application July 12, 1938, Serial No. 218,863

7 Claims. (Cl. 153—48)

This invention relates to a method and apparatus for removing pits in the surface of metal sheets.

In the manufacture of stainless steel sheets, 5 inclusions oftentimes occur which result in voids in the metal at or beneath the surface and the polishing operations which are necessary to make the sheets acceptable to most industries disclose the presence of such voids or pits as occur at the surface and, unless they are successfully removed, the sheets are rejected.

The present practice of removing the pits involves a hand grinding operation subsequent to the initial polishing operation. This grinding 10 operation entails grinding the surface of the sheet over an area having a radius of three or four inches with the pit as the center, the ground area being tapered from the outer edge thereof to the bottom of the pit. This tapering is necessary in order that the reduction in thickness 15 of the sheet which is required to remove the pit will not be apparent and it not only results in an appreciable loss of valuable metal but involves a highly skilled labor operation. As a sheet may 20 have anywhere from a few to twenty or thirty pits, the expense of removing them so as to render the sheets commercially acceptable is considerable, not only on account of the actual labor cost of the operation and the loss of metal, but 25 also on account of the interruption which it occasions in the flow of production.

The principal object of the present invention is to provide a method and an apparatus whereby 30 pits in the polished surfaces of metal sheets may be more expeditiously and economically removed. In general, this object is attained by applying sufficient pressure to the back of the sheet in an area opposed to the pit to be removed to cause metal adjacent the lower portion of the pit to 35 flow toward and flush with the polished surface of the sheet.

A primary feature of the invention consists in providing a member for engaging the surface of the sheet surrounding the pit to be removed 40 and means for applying pressure to the other surface of the sheet in an area directly opposed to the pit for causing metal adjacent the lower portion of the pit to flow toward said member and flush with the surface of the sheet in engagement therewith.

Another feature of the invention consists in providing opposed members for clamping portions 45 of the sheet surrounding the pit to be removed, one of the members having a substantially flat face adapted to engage the surface of the

sheet having the pit and movable means being associated with the other of the members for applying pressure to the other surface of the sheet in an area directly opposed to the pit.

Another feature of the invention resides in 5 providing resilient means preferably in the form of a rubber plug which is engageable with the sheet in an area directly opposed to the pit to be removed and which is capable of being subjected to sufficient pressure so as to cause metal 10 adjacent the lower portion of the pit to flow toward the surface of the sheet having the pit.

Other and more specific features of the invention, residing in advantageous forms, combinations and relations of parts, will hereinafter appear and be pointed out in the claims.

In the drawings, illustrating a preferred embodiment of the invention,

Figure 1 is a side elevational view of the pit removing machine. 20

Figure 2 is a plan view of the machine.

Figure 3 is a front elevational view of the machine.

Figure 4 is a vertical sectional view taken on line 4—4 of Figure 2. 25

Figure 5 is a fragmentary vertical sectional view taken on line 5—5 of Figure 4.

Figure 6 is a detail view, partly in elevation and partly in section, taken on line 6—6 of Figure 4. 30

Figure 7 is a sectional view taken on line 7—7 of Figure 1.

Figure 8 is a detail fragmentary sectional view taken on line 8—8 of Figure 6.

Figure 9 is a plan view of a perforated rubber 35 disk employed in the machine.

Referring more particularly to the drawings, 40 it indicates the frame of the machine which may advantageously be formed as a substantially integral casting having upper and lower jaws or parts 2 and 3, respectively. The bottom of the frame may be conveniently formed with pads or the like 4 and 5, respectively, which are adapted to rest upon and be secured to suitable supports, such, for example, as I-beams 6 and 7. 45

Rigidly mounted on the forward end of each of the jaws is a cylinder, the one on the upper jaw being designated by the reference numeral 8 and the one on the lower jaw being designated by the reference numeral 9. Each of the cylinders is provided with laterally projecting flanges 10 which are rigidly secured as by bolts 11 to corresponding flanges 12 formed integrally with the respective jaws of the frame. To relieve the securing bolts 11 from shear, each of the cylinders 50 55

may be provided with a rearwardly extending rib 13 which fits snugly within a suitably shaped recess formed in the front end of the adjacent jaw of the frame.

5 Movable mounted within the upper cylinder 8 is a hydraulic ram 14 and disposed above the ram is a flexible diaphragm 15 which is clamped between the cylinder and the head 16, the head being secured to the cylinder by bolts 17. The 10 head is provided with a port 18 through which fluid under pressure from a suitable source, to be hereinafter described, is admitted through a pipe 19 into the cylinder to actuate the diaphragm 15 and ram 14. The ram is normally 15 maintained in an elevated position by a spring 20 which is interposed between a shoulder 21 formed on the ram and a ledge or shoulder 22 provided on the interior of the cylinder.

Secured to the lower end of the ram 14 by a 20 plurality of countersunk screws or the like 23 is a preferably horizontally disposed plate-like member 24 which carries a member 25 provided in its lower portion with a steel anvil 26 having a flat bottom surface adapted 25 to engage the surface of the sheet from which pits are to be removed. As it is desirable, for a purpose to be hereinafter explained, to enable the member 25 and the anvil 26 to be moved rearwardly with respect to the ram 14, member 30 25 is slidably connected to the plate-like member 24 by means of oppositely disposed channels 27 which are respectively secured, as by bolts 28, to laterally projecting flanges 29 with which the upper portion of member 25 is provided. The 35 upper legs or flanges 30 of the channels 27 fit within notched-out portions formed in the side edges of plate member 24, while the lower legs 31 of the channels extend beneath the lateral flanges 29 of member 25.

Anvil 26 and member 25 are locked or maintained in their normal operative positions by a pin 32 which is slidably mounted within a housing which may be advantageously screw threaded into the web of one of the channels 27. A spring 34 which is disposed within the housing and encircles the pin, normally urges the inner end of the pin into an opening 35 formed in the adjacent flange 29 of member 25, the pin being provided with an annular flange 36 which is adapted to abut against the outer edge of flange 29 and affords a shoulder against which the spring 34 bears. The outer end of the pin may be provided with suitable means 37 whereby it may be easily retracted to withdraw the inner end of the pin from opening 35 and thus enable the anvil and member 25 to move rearwardly. To limit the extent of rearward movement of member 25, the inner end of plate member 24 may be conveniently provided with a depending portion 38.

The inner portion of plate member 24 may also be provided with a pin 39 which extends upwardly into an opening 40 formed in the bottom of the cylinder 8. This pin is adapted to move up and down within opening 40 in accordance with corresponding movements of the ram and it serves to prevent the ram and the parts carried thereby from rotating on a vertical axis.

The anvil 26 which fits within a socket formed in the lower end of member 25 is removably carried thereby by a ring-like member 41 having an 70 inwardly projecting annular flange 42 which underlies an outwardly extending annular flange 43 formed on the anvil, the ring 41 being secured to member 25 by a plurality of screws 44. Interposed between the upper end of the

anvil and the adjacent portion of member 25 is a perforated rubber disk 45, shown in detail in Figure 9, which enables the anvil to angle slightly in order that the bottom face thereof will accommodate itself to the surface of the sheet which it is intended to engage. Thus regardless of the lack of parallelism of the upper and lower surfaces of the sheet or any deflection which may occur in the frame of the machine due to the loads applied, the rubber disk enables the 10 anvil to adjust itself to permit its flat lower surface to bear uniformly upon the adjacent surface of the sheet.

Mounted on the upper end of the lower cylinder is a fixed anvil 46 which affords a support for the sheet to be worked upon. The anvil may be rigidly and at the same time removably secured to the cylinder by a ring member 47 which has an inwardly projecting annular flange 48 adapted to overlappingly engage an outwardly projecting annular flange 49 on the anvil, the ring being secured to the cylinder by a plurality of screws 50. The center of the anvil 46 is provided with a chamber in which a rubber plug 51 mounted on the upper end of a plunger 52 is disposed. While the body portion of the plunger may be conveniently made in the form of a cone, the upper portion thereof which projects for a limited distance into the chamber in the anvil is of cylindrical shape in cross section, its diameter being 30 only about .0002 inch less than the diameter of the chamber. This effectively prevents the rubber plug from being extruded between the plunger and the adjacent part of the anvil and yet provides the necessary clearance to enable the 35 plunger to move slightly with respect to the anvil. The rubber plug may, of course, be removably connected to the upper end of the plunger, if that is found desirable, and it is to permit inspection of the plug and replacement thereof 40 when it becomes worn that the upper anvil and member 25 are movable rearwardly with respect to the ram in the upper cylinder.

The plunger 52 has a relatively broad base and seats within a cup-shaped member 53 disposed 45 within a socket formed in the upper end of a ram 54 with which the lower cylinder is provided. The plunger is firmly secured in place by a cap member 55 which is screw threaded on the upper end of the ram and is provided with an inwardly 50 projecting annular flange 56 which overlappingly engages an annular flange 57 on the base of the plunger.

In the lower end of cylinder 9 is a flexible diaphragm 58 which is clamped in place between the 55 cylinder body and the cylinder head 59, the latter being provided with a port 60 through which fluid under pressure is admitted from pipe 61 to actuate the diaphragm and ram, the fluid which is delivered to the bottom cylinder being from the 60 same source and under the same pressure as the fluid delivered to the upper cylinder. The purpose of the diaphragms in the upper and lower cylinders is to eliminate the use of packing around the rams past which leakage of the fluid under 65 pressure might occur due to the exceedingly short stroke of the ram and the high pressures involved. Such leakage would, of course, be objectionable on the sheet and would otherwise interfere with the operation.

Like the ram of the upper cylinder, the ram of the lower cylinder is provided with a spring 62 which is interposed between the shoulder 63 on the interior of the cylinder and a shoulder 64 on the ram. Spring 62, however, is stronger than 75

the spring 20 for the ram in the upper cylinder so that, when the pressure, acting on both rams from a common source of supply, is released, the lower ram will return to its normal inoperative position a split second before the upper ram returns and thus prevent the extension of the rubber plug 52 above the top surface of the lower anvil.

In the actual practice of removing the pits, 10 circles may be marked on the sheet around each of the pits to be removed as a center, the circles being made by a pencil or any other suitable means which will not mar the surface and being preferably of a diameter corresponding to the 15 diameter of the upper anvil 26. Thus, when the sheet is placed in the machine between the anvils, the circle serves to locate or position the pit to be removed directly above the rubber plug, which is advantageously of about one-half inch in 20 diameter. The pits occurring in the sheets may have a diameter of .01 inch or more and a depth of .004 inch or .005 inch and may occur in clusters or individually.

The sheets may be conveniently supported on 25 ball top tables, not shown, for delivery to the machine, the tops of the tables being on the same level as the upper surface of the lower anvil. When the sheet has been properly positioned in the machine between the anvils, fluid under pressure is admitted to the upper cylinder first to 30 move ram 14 downwardly and thus cause anvil 26 to rigidly clamp the sheet to anvil 46. Pressure is then admitted to the lower cylinder to force the rubber plug 51 into engagement with the 35 back of the sheet in a localized area directly opposed to the pit to be removed. The area of the upper ram which is subjected to the fluid under pressure is greater than the area of the lower ram subjected thereto and, therefore, a greater total 40 load will be exerted by the upper ram on the sheet than will be exerted by the lower ram. The sheet will, therefore, be firmly held in engagement with the lower anvil even after pressure has been admitted to the lower cylinder. By applying pressures of the order of two hundred thousand 45 pounds per square inch, the rubber plug 51 will cause the metal adjacent the lower portion of the pit to flow upwardly toward the upper anvil 26 and flush with the upper surface of the sheet 50 and thus entirely eliminate the pit. The rubber plug will impart a slight depression to the back of the sheet where it does no harm and, because of its ability to conform to any irregularities of the back of the sheet, it will transmit a uniform 55 pressure and will not make any tool mark on the sheet. The portions of the lower anvil defining the opening in which the rubber plug is located furnish a lateral support for the plug and notwithstanding the magnitude of the pressure to 60 which the plug is subjected, extrusion thereof will not occur between the upper surface of anvil 46 and the bottom surface of the sheet, because the portions of the sheet engaging the upper surface of the anvil will be maintained in tight engagement therewith due to the ability of the upper anvil by virtue of the perforated rubber disk 45 to exert a uniform pressure on all portions of the sheet it engages irrespective of any lack of parallelism of the upper and lower surfaces of 65 the sheet and any possible deflection which may occur in the frame of the machine on account of the loads involved.

Upon completion of the pit removal operation, the ram of the lower cylinder may be relieved of 70 fluid pressure before the upper ram, in order that

the rubber plug will not be projected above the top surface of the lower anvil, but I have found that, by providing the lower ram with a stronger release spring than the upper ram, pressure may be relieved from both rams simultaneously and 5 still the rubber plug will not be projected beyond the lower anvil, since the heavier spring acting on the lower ram will serve to cause that ram to return a fraction of a second before the upper ram returns. If desired, however, the return 10 strokes of the ram may be made hydraulically by suitably timed pressure means instead of using springs.

The cycle of operation of the machine takes place in about five seconds and it will, therefore, 15 be readily apparent that a badly pitted sheet may be completely treated in from less than a minute to several minutes. As it requires from ten to fifteen minutes to remove a single pit by using the hand grinding method heretofore described 20 which, up to the present time, has been accepted as being the most efficient manner of removing pits, the commercial value of the present invention will be immediately recognized.

While any well known and conventional means 25 may be employed for supplying fluid under pressure to the cylinders of the machine, there is illustrated in the drawings mechanism which has been found to be well suited for that purpose. This mechanism includes a fluid reservoir or tank 30 65 which may be conveniently located on top of the frame of the machine. Mounted on top of the tank is a pump 66 which is preferably of the rotary type having an inlet pipe 67 extending downwardly into the liquid within the tank. The 35 pump may be driven from any suitable source of power, such as an electric motor 68, which may be conveniently mounted on the tank adjacent the pump. The fluid under pressure from the pump passes through a pipe 69 to a relief valve 40 70 which is of such construction that, when the maximum pressure is reached on the pump, excess pump displacement passes from the relief valve back into the supply tank through pipe 71. Normally, however, fluid under pressure from 45 the pump passes directly to relief valve 70 and thence through a pipe 72 to a four-way valve 73, which is preferably provided with a piston type valve. A check valve 74 may be located in pipe 72 to prevent the back flow of fluid to the pump. 50

The four-way valve 73 has one port communicating with pipe 19 through which fluid under pressure is delivered to the upper cylinder; an other port communicating with pipe 75 through which fluid passes to a valve 76 for controlling 55 the flow of fluid through pipe 61 into the lower cylinder 9; and another port communicating with a pipe 77 through which fluid may flow from the four-way valve back into the supply tank 65. The valve 76 controls the rate of flow of the fluid from 60 pipe 75 to pipe 61 and it is of such construction that the fluid may not flow therethrough in the reverse direction. There is a by-pass 78, however, around the control valve 76 connecting pipes 61 and 75 through which the fluid may return from 65 the lower cylinder through the four-way valve to the supply tank, a check valve 79 being located within the by-pass to prevent fluid under pressure from passing through the by-pass to the lower cylinder. The control valve is preferably 70 provided with a port communicating with a pipe 80 through which seepage from the valve may return to the supply tank.

The piston valve of the four-way valve 74 is connected to a rod 81 which is secured at its lower 75

end to an arm 82 rigidly mounted upon a rock shaft 83 which extends longitudinally of the machine and is journaled in suitable brackets carried by a beam or the like 84 secured to the 5 I-beam supports 6 and 7 of the machine. At its forward end, the shaft 83 is provided with a treadle 85 whereby it may be conveniently rotated by an operator to induce the desired movement of the piston valve. The rod which connects shaft 83 with the piston valve is preferably encircled by a spring 86 for maintaining the rod as well as the treadle 85 in an elevated position.

When the treadle is in its uppermost position, the piston valve is in such position that pipes 15 19 and 75 which respectively lead to the upper and lower cylinders from the four-way valve are in open communication with the exhaust pipe 77 leading from the four-way valve to the supply tank. When the treadle is depressed approximately one-half of the distance it is capable of being moved, the port of the four-way valve communicating with pipe 19 is in open communication with the port connected to pipe 72, but the port of the valve leading to pipe 75 remains 20 in open communication with the port leading to pipe 77. Thus, when the treadle is in this position, fluid under pressure is supplied to the upper cylinder but not to the lower cylinder. When the treadle is completely depressed, the position 25 of the piston valve is such that fluid under pressure is still supplied to the upper cylinder but the port leading to pipe 75 has been opened to communication with pipe 72, while the port leading to the exhaust line 77 has been blocked. In this position of the treadle, therefore, fluid under pressure is supplied to both cylinders. To release fluid pressure from the cylinders, all that is required is to relieve the treadle from the force 30 required to operate it, whereupon the piston valve, as well as its operating parts, will return to its normal position heretofore described.

From the foregoing, it will be perceived that I have devised a comparatively simple method and apparatus for effectively and with a minimum of effort and requiring the exercise of little skill for removing pits from the polished surfaces of metal sheets. It is manifest that various modifications may be made in the specific apparatus herein disclosed to effect this end without departing 45 from the spirit and scope of the invention as defined in the appended claims.

What I claim is:

1. A machine for removing pits and the like from a metal sheet, said machine including a member adapted to engage the surface of the sheet surrounding the pit, elastic means engageable with the other surface of the sheet for applying pressure thereto in an area directly opposed to said pit for causing metal adjacent the lower portion of the pit to flow toward said member and flush with the surface of the sheet in engagement therewith, and means whereby said elastic means during transmission of pressure therefrom to said sheet is restrained against deformation otherwise than in conformity to change in the adjacent surface of the sheet.

2. A machine for removing pits and the like from a metal sheet, said machine including opposed members for clamping portions of the sheets surrounding the pit, one of said members having a substantially flat face adapted to engage the surface of the sheet having the pit, movable means including a rubber plug engageable with the other surface of the sheet for applying pressure thereto in an area directly opposed to

said pit for causing metal adjacent the lower portion of the pit to flow toward and flush with the surface of the sheet having the pit, and means cooperable with the plug during transmission of pressure therefrom to the sheet for restraining deformation of the plug otherwise than in conformity to change in the adjacent surface of the sheet.

3. A machine for removing pits and the like from a metal sheet, said machine including a member adapted to engage the surface of the sheet surrounding the pit, a support for the sheet engageable with the other surface thereof, said member being movable downwardly to clamp the sheet to said support, and means associated with said support for applying pressure to the surface of the sheet in engagement therewith in an area directly opposed to said pit for causing metal adjacent the lower portion of the pit to flow toward and flush with the surface of the sheet having the pit, said means including an elastic member engageable with the sheet, said elastic member when applying pressure to the sheet being restrained by said support from expanding laterally.

4. A machine for removing pits and the like from a metal sheet, said machine including opposed members for clamping portions of the sheets surrounding the pit, one of said members having a substantially flat face adapted to engage the surface of the sheet having the pit and the other of said members being engageable with the opposite surface of the sheet and being provided with a chamber adapted to be closed by the sheet, elastic means disposed within said chamber, and means movable within said chamber for forcing said elastic means into engagement with the last named surface of the sheet in an area directly opposed to said pit for causing metal adjacent the lower portion of the pit to flow toward and flush with the surface of the sheet having the pit, said chamber preventing lateral expansion of the elastic means during transmission of pressure therefrom to the sheet.

5. A machine for removing pits and the like from a metal sheet, said machine including a sheet supporting member, and means movable toward said sheet supporting member for clamping the sheet thereto, said means comprising a head having a flat surface engageable with the surface of the sheet having the pit, pressure responsive means for actuating said head and resilient means interposed between the fluid pressure responsive means and the head enabling the flat surface thereof to accommodate itself to the plane of the surface of the sheet engageable thereby, said supporting means having a chamber adapted to be closed by the sheet, a rubber member disposed within said chamber, and means for forcing said rubber member into engagement with the adjacent surface of the sheet in an area directly opposed to the pit to be removed for causing metal adjacent the lower portion of the pit to flow toward and flush with the surface of the sheet having the pit, said chamber preventing lateral expansion of the rubber member during transmission of pressure therefrom to the sheet.

6. A machine for removing pits and the like from a metal sheet, said machine including opposed means for clamping portions of the sheet surrounding the pit, one of said means being engageable with the surface of the sheet having the pit, the other of said means comprising a member engageable with the opposite surface of

the sheet and having a chamber adapted to be closed by the sheet, elastic means disposed within said chamber and being of substantially the same cross sectional area as the latter, and means movable within said chamber for forcing said elastic means into engagement with a portion of the sheet adjacent thereto for causing metal adjacent the lower portion of the pit to flow toward said first named means and flush with the surface of the sheet in engagement therewith, said elastic means when applying pressure to the sheet being restrained by said chamber against deformation which would increase the projected area of the portion of the elastic means in engagement with the sheet.

7. The method of removing pits from the polished surface of a metal sheet which consists in rigidly clamping portions of the sheet surrounding the pit to be removed, and in forcibly pressing against the back of the sheet within the area of the clamped portion thereof and in a localized area directly opposed to the pit with elastic means which is restrained against deformation increasing the projecting area thereof in engagement with the sheet whereby metal adjacent the lower portion of the pit is caused to flow toward and flush with the polished surface of the sheet.

DAVID E. MULHOLLAND. 15
